SELF-EJECTING ELECTRIC PLUG

Filed Nov. 21, 1949

FIG. 1

FIG. 2

INVENTOR.
JOHN J. MAISEY

BY

Wm. H. Dean

AGENT

UNITED STATES PATENT OFFICE

2,571,046

SELF-EJECTING ELECTRIC PLUG.

John J. Maisey, Palm City, Calif.

Application November 21, 1949, Serial No. 128,609

3 Claims. (Cl. 173—361)

1

My invention relates to a self-ejecting electric plug, and more particularly to an improvement over my co-pending application, Serial No. 109,332, filed August 9, 1949, now abandoned, and the objects of my invention are:

First, to provide a self-ejecting electric plug of this class having improved ejector latch means, which is very readily and easily released when a relatively small amount of pressure is applied thereto;

Second, to provide a self-ejecting electric plug of this class which is very positive in operation and easy to manipulate;

Third, to provide a self-ejecting electric plug of this class in which all of the parts may be readily cast of plastic or the like, for facilitating production thereof;

Fourth, to provide a self-ejecting electric plug of this class which is very neat and compact;

Fifth, to provide a self-ejecting electric plug of this class which is very simple and easy to assemble; and

Sixth, to provide a self-ejecting electric plug of this class which is very simple and economical of construction, efficient in operation, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, forming a part of this application, in which:

Fig. 1 is a longitudinal sectional view of my self-ejecting electric plug, showing parts and portions in elevation to facilitate the illustration; and Fig. 2 is a transverse sectional view, taken from the line 2—2 of Fig. 1.

Similar characters of reference refer to similar parts and portions throughout the several views of the drawings.

The frame 1, end plate 2, conductor prongs 3 and 4, ejector 5, springs 6 and 7, plunger 8, and the conductors 9 and 10, constitute the principal parts and portions of my self-ejecting electric plug.

The frame 1, as shown in Fig. 1 of the drawings, is a substantially cup-shaped member, having a partially enclosed end portion 1a, provided with a bore 1b therein, in which the plunger 8 is reciprocally mounted. Communicating directly with the bore 1b is an enlarged bore portion 1c, having a latch ledge 1d at the inner terminus

2

thereof, which projects inwardly of the bore 1c, and is substantially smaller in diameter than said bore 1c. This annular latch portion 1d is adapted to be engaged by the segment latch fingers 5a of the ejector 5. The ejector 5 is reciprocally mounted in a central bore portion 2a of the end plate 2, which is positioned in an annular recess 1e in the opposite end of the frame 1 from the partially enclosed portion 1a, and abuts the shoulder 1f at the inner terminus of the recess 1e, all as shown best in Fig. 1 of the drawings.

The end plate 2 is provided with a pair of openings 2b and 2c, at opposite sides of the bore 2a, through which the conductor prongs 3 and 4, respectively, extend. These conductor prongs 3 and 4 are fixed to the end plate 2 by means of screws 3a and 4a, respectively, which are screw-threaded in the end plate 2, all as shown best in Fig. 1 of the drawings. As shown in Fig. 2 of the drawings, the conductor prongs 3 and 4 are provided with secondary terminal screws 3b and 4b, to which the conductors 9 and 10, respectively, are connected. The ejector 5 is a cup-shaped member, having a cylindrical body portion 5b, integral with which are segmental resilient fingers 5a, having buttress latch portions 5c projecting laterally therefrom. The ends of these buttress latch portions 5c are provided with beveled portions 5d, adapted to engage the inward bevel of the inwardly projecting latch portion 1d of the frame 1, as hereinbefore described. At the transition of the body 5b and segmental fingers 5a is a shoulder portion 5e, which abuts the inner side of the plate 2 for resisting the compression of the spring 6, which tends to force the ejector 5 outwardly of the end plate 2.

It will be noted that the segmental fingers 5a are separated by slots 5f, providing for the resilient deflection of the fingers 5a inwardly and outwardly in their engagement and release from the latch ledge portion 1d hereinbefore described. The ejector 5 is provided with an internal bore 5h, in which the shank 8a of the plunger 8 is reciprocally slidably mounted. This shank 8a of the plunger 8 is hollow and contains the spring 6, which is abutted at its one end at the end portion 5j of the ejector 5, and at its opposite end in the head portion 8b of the plunger 8, all as shown best in Fig. 1 of the drawings.

Integral with the head portion 8b of the plunger 8 is an enlarged diameter skirt portion 8c, having an internal outwardly and angularly directed bevel portion 8d, adapted to engage the bevel portions 5d of the segmental fingers 5a. The spring 7 is abutted at its one end on the

abrupt transition between the bore portions 1b and 1c of the frame 1, and is abutted at its opposite end on the transition shelf between the head portion 8b of the plunger 8 and the skirt 8c thereof. The spring 7 tends to force the plunger 8 toward the ejector 5 and exerts slight pressure substantially less than required to release the ejector 5 from the annular latch ledge 1d.

The operation of my self-ejecting electric plug is substantially as follows: When the conductor prongs 3 and 4 are inserted in a conventional female electrical outlet plug, the ejector 5 engages the conventional face plate of the female plug and is forced inwardly of the frame 1, telescoped over the shank 8a of the plunger 8, and the inclined portions 5d of the segmental fingers 5a are engaged with the beveled portion of the annular latch ledge 1d and caused to deflect inwardly until they pass the latch ledge 1d, whereupon they expand, and the buttress latch portions 5c engage the latch ledge 1d at its upper side, as shown in Fig. 1 of the drawings. When the ejector 5 is forced inwardly until the buttress portions 5c engage the latch ledge 1d, the spring 6 is considerably compressed and tends to force the ejector 5 outwardly of the end plate 2, into the position as shown in Fig. 1 of the drawings. When it is desired to release my self-ejecting electric plug from the female outlet plug, slight pressure is exerted on the face 8e of the plunger 8, which causes the inclined portions 8d to engage the inclined portions 5d of the segmental fingers 5a, tending to compress them inwardly, which releases the buttress latch portions 5c from the annular latch ledge 1d, permitting the spring 6 to force the plunger 8 outwardly in engagement with the face plate of the conventional female plug, which ejects the frame 1, together with end plate 2 and the conductor prongs 3 and 4, whereby axial removal of the conductor prongs 3 and 4 is automatically accomplished, preventing twisting and bending thereof, and the exertion of considerable effort in the removal of the plug from the conventional female outlet plug. In operation, the spring 7 merely maintains the plunger 8 at its inclined portions 8d in engagement with the inclined portions 5d of the segmental fingers 5a, so that slight pressure on the face 8e of the plunger 8 causes instant release of the ejector 5, so that it may quickly and easily release said ejector 5.

Though I have shown and described a particular construction, combination and arrangement of parts and portions, I do not wish to be limited to this particular construction, combination and arrangement of parts and portions, but desire to include in the scope of my invention the construction, combination and arrangement substantially as set forth in the appended claims.

Having thus described my invention, what I

claim as new and desire to secure by Letters Patent is:

1. In a self-ejecting electric plug, a frame, a plunger in said frame having a portion thereof projecting from one end of the frame, an ejector reciprocally mounted in said frame in opposed relationship to said plunger, a spring tending to force said plunger and said ejector away from each other, whereby said spring tends to force said ejector outwardly of said frame, a pair of conductor prongs parallel with said ejector and substantially coextensive therewith when extended, said frame having an inwardly projecting latch ledge, said ejector having a plurality of resilient segmental fingers provided with buttress latch portions, adapted to engage said inwardly disposed ledge of said frame and means for releasing said segmental fingers from said ledge.
2. In a self-ejecting electric plug, a frame, a plunger in said frame having a portion thereof projecting from one end of the frame, an ejector reciprocally mounted in said frame in opposed relationship to said plunger, a spring tending to force said plunger and said ejector away from each other, whereby said spring tends to force said ejector outwardly of said frame, a pair of conductor prongs parallel with said ejector and substantially coextensive therewith when extended, said frame having an inwardly projecting latch ledge, said ejector having a plurality of resilient segmental fingers provided with buttress latch portions, adapted to engage said inwardly disposed ledge of said frame, said plunger having an annular beveled portion adapted to engage said buttress latch portions of said segmental fingers for forcing the same inwardly, and releasing the same from said inwardly disposed latch ledge of said frame.
3. In a self-ejecting electric plug, a frame, a plunger reciprocally mounted in said frame and having one end thereof projecting outwardly of said frame, an ejector reciprocally mounted in the opposite end of said frame axially aligned with said plunger, a spring interposed between said plunger and said ejector, said frame provided with an inwardly projecting latch portion, said ejector provided with resilient finger means engageable with said latch portion of said frame, said plunger provided with angular cam means for releasing said resilient fingers from said latch shelf portion of said frame.
